We claim the ornamental design for a temperature and humidity transmitter, as shown and described.

(21) Appl. No.: **29/772,925**

DESCRIPTION

(22) Filed: **Mar. 4, 2021**

FIG. 1 is a front, left and bottom perspective view of a temperature and humidity transmitter according to our new design;

(51) LOC (13) Cl. **10-04**

FIG. 2 is a rear, top and right side perspective view of the temperature and humidity transmitter of FIG. 1.

(52) U.S. Cl. **USPC D10/53**

FIG. 3 is a front elevational view of the temperature and humidity transmitter of FIG. 1

(58) **Field of Classification Search**

FIG. 4 is a rear elevational view of the temperature and humidity transmitter of FIG. 1;

USPC D10/52, 53, 56

FIG. 5 is a left side view of the temperature and humidity transmitter of FIG. 1;

CPC G01D 1/245; G01B 5/30; G01M 5/0075;

FIG. 6 is a right side view of the temperature and humidity transmitter of FIG. 1;

G01N 29/045; G01N 29/12; G01N
29/2475; G01N 29/2481; G01J 1/429;

FIG. 7 is a top plan view of the temperature and humidity transmitter of FIG. 1; and,

A61B 5/04; A61B 5/0059; A63B
24/0084; A63B 24/0062; A63B 24/0075;

FIG. 8 is a bottom plan view of the temperature and humidity transmitter of FIG. 1.

A63B 69/0028; A63B 71/0622; A63B
71/0686; A63F 13/00; A63F 13/06; A61N

The broken lines depict portions of the temperature and humidity transmitter in which the design is embodied that
form no part of the claimed design.
